UNITED STATES PATENT OFFICE.

HENRY A. WISE WOOD, OF NEW YORK, N. Y., ASSIGNOR TO WOOD & NATHAN COMPANY, OF NEW YORK, N. Y., A CORPORATION OF NEW YORK.

MECHANISM FOR PRINTING FROM INTAGLIO PRINTING-PLATES.

1,208,878.

Specification of Letters Patent. Patented Dec. 19, 1916.

Application filed September 30, 1905, Serial No. 280,752. Renewed May 22, 1916. Serial No. 99,212.

To all whom it may concern:

Be it known that I, HENRY A. WISE Wood, a citizen of the United States, residing at New York, in the county of New York and State of New York, have invented new and useful Mechanisms for Printing from Intaglio Printing-Plates, of which the following is a specification.

The object of this invention is to provide improved mechanisms for printing from "intaglio" printing plates.

The customary method of printing from "intaglio" or printing plates with the design cut or etched therein consists in inking the plates, wiping or scraping off the surplus ink so as to leave ink only in the depressions, and then pressing the sheet of paper onto the plates.

By this improvement it is possible to arrange a printing press of ordinary construction, such as a printing-press employing a reciprocating member or bed, or a platen printing press to print from "intaglio" printing plates. In adapting the invention to presses of this character, a receptacle is provided so that the surplus ink removed by the scraper from the printing plate is deposited in the receptacle.

The preferred way of practising the invention is to apply the same to the mechanism in such way that a state of oppositely reciprocating movement will exist between the printing plate and scraper, and to actuate the scraper so that preferably it will act on the plate on a movement in but one direction, preferably just before printing. In this preferred form of mechanism, provision is preferably made for immediately removing the surplus ink from the scraper and depositing or carrying the same to the receptacle adapted to receive the surplus ink.

The invention further consists of certain arrangements and combinations hereinafter described in the specification and pointed out in the claims.

The invention is illustrated in the accompanying drawing forming part of this application for patent, which is a side elevation of a two-revolution printing press illustrating the preferred form of the invention.

From earliest times in the art of printing it has been recognized that printed products of artistic merit could best be produced from printing plates engraved or etched in intaglio; and in more recent times the me-

chanical perfection of intaglio printing plates has been greatly increased by various photo-etching processes.

In order to do artistic printing from intaglio printing plates, particularly in order to produce satisfactory results from photo-etched plates, it is necessary to wipe the surface of the plate free from ink without disturbing the ink which should be retained in the very fine "stipple" or minute cells which are etched or engaged into the face of the plate.

The art of printing from intaglio printing plates is an art practised with best results by hand, and by the aid of the judgment and experience of skilled specialists in plate-printing.

In the ordinary hand-press for plate printing the inking of the plate is the part of the operation which requires the most skill and judgment. A skilled plate-printer after having inked the surface of his plate is required to use great care in wiping off the surface of the plate, and although some printers have attempted to use various wipers of soft material, it has been found in practice that the most artistic and satisfactory results are produced by workmen who use the palms of their hands in cleaning the surfaces of their plates before the successive sheets are laid thereon to be imprinted by their presses.

A number of different constructions have been proposed for mechanically printing from intaglio printing plates. In most instances the machines have been designed to follow as closely as possible the steps of hand-printing. In one typical form of such machines it was proposed to drag the plates in horizontal orbits by chains, so that the plates would be successively carried past inking devices, and past wiping devices for cleaning off the surplus ink, the sheets being placed upon the plates by hand. In these machines, as in all other machines for mechanically printing from intaglio printing plates it was proposed to use cushioned wipers of chamois-skin or other soft material. These machines are not capable of producing the highest grade of artistic work, for the reason that the wipers will press into the intaglio and tear out the finer points, or stippling, of the plate, and will also remove the ink from the smaller interstices of the plate, which ink should

be retained in order to produce the best results, especially from photo-etched plates.

I have discovered that printing presses of ordinary type, to wit: reciprocating printing presses including bed-and-cylinder machines, in which a reciprocating bed carries the plates into contact with sheets of paper on an impression cylinder; or bed-and-platen machines in which the impression is 10 made between a type-carrying bed and cooperating platen can be used for producing artistic printing from intaglio printing plates by providing such printing presses with scrapers or blades which can be adjusted to scrape off the surplus ink from the surfaces of intaglio printing plates, without ripping out or breaking down the stipple or fine points of the design, and without removing the ink contained even 15 in the finer depressions of the intaglio plates.

In an art remote from printing paper from intaglio printing plates it has been proposed to use scraping blades. This has 20 been done in removing the surplus pigments from the engraving rollers employed in printing calicoes.

In the art of calico printing, the engraved pattern-rollers revolve in troughs or fountains containing the desired pigments, and in connection with these printing rollers, scrapers or so-called "doctor" blades are employed for scraping off surplus ink. This is, however, a quite different application 25 of a scraper or blade from that contemplated by my invention, in which the scraper or blade is used in connection with the very fine depressions of intaglio printing plates as distinguished from the pattern-rollers used in calico printing, which are costly, engraved by hand, and are entirely without the "stipple" or delicate texture of the etched plates used in printing 30 on paper.

Another characteristic difference between 45 my invention and the constructions employed in calico printing is that I have found it desirable to provide a receptacle distinct and separate from the ink fountain 50 to receive the surplus ink which is scraped off; while in calico printing the surplus pigments are allowed to return directly to their color troughs.

The invention will be best understood by 55 describing the mechanism in detail.

Referring to the mechanism shown in the drawing, A designates the framing; B the reciprocating printing member or bed; and C the impression cylinder of an ordinary 60 printing press such as a printing press of the well-known two-revolution type. P designates the intaglio printing plate or plates which may be secured to the bed in any desired way. F designates the ink fountain, 65 and G the form inking rollers. T designates

an ink table carried by the bed. Ink is taken from the ink fountain F by means of a suitable doctor roller and placed upon the ink table T which carries the ink to the form inking rollers G which in turn lay 70 the same upon the printing plate or plates. These parts may be arranged as is common in printing presses of the type described.

The sheets are fed to the impression cylinder from the usual feed member and are 75 delivered from the impression cylinder by any suitable delivery mechanism, as indicated in the drawings. The impression cylinder is raised and lowered in the usual way so that it contacts with the printing plate on the forward stroke of the bed, and so that it clears the printing plate on the return stroke of the bed.

S designates the scraper which is made out of a piece of thin metal, preferably 85 ground to a fine accurate edge. This scraper S is secured to arms 10 which are pivoted on a shaft 11 journaled in suitable brackets 12. One of the arms is connected to a rod 13 which carries a roller 14 bearing on a 90 cam 15 arranged on the cam-shaft of the machine, which shaft makes one turn for each complete forward and backward movement of the printing member or bed.

The rod 13 is arranged in a suitable guide 95 16 and the roll 14 is held to its cam by a spring 17. The cam 15 is so arranged that as the bed makes its forward or printing movement, the scraper S will be moved down to contact lightly and accurately with the printing-plate. A roller 18 is secured to said shaft 11. This roller is driven by any suitable gearing, such as indicated in dotted lines, and this gearing is preferably arranged so that the peripheral speed of the 100 roll will be greater than the speed at which the bed moves forward on its printing stroke. A receptacle R is arranged behind the roller 18 and a scraper or ink remover 19 is arranged between the receptacle R and the roller 18. In this arrangement, as the scraper S removes the surplus ink from the printing plate or plates, the roller 18 will take this ink from the scraper and the scraper 19 will remove the surplus ink from 105 the roller 18 and guide the same into the receptacle R which will prevent the surplus ink from backing up or crowding on the plate as the bed makes its printing movement. By this arrangement, intaglio printing 110 can be effected from intaglio printing plates at a speed at which ordinary printing is done.

The construction shown is the preferred 115 arrangement in that the ink removed by the scraper from the printing plate or plates is immediately carried away from the scraper instead of being forced back upon the printing plate.

Many other arrangements and modifica- 120 125 130

tions may be devised for constructing my invention by a skilled mechanic without departing from the scope of my invention as expressed in the claims.

5 Having thus fully described my invention, what I claim and desire to secure by Letters Patent is:—

1. In mechanism for printing from intaglio printing plates, the combination of a 10 printing member having a to-and-fro movement, a scraping blade, means for causing the blade to contact with the printing member upon alternate movements thereof, and a cleaning device, the surface of which has 15 a movement along the surface of the blade and is constantly in contact therewith for removing refuse ink therefrom.

2. In a mechanism for printing from intaglio printing plates, the combination of 20 an impression member, a printing member for carrying the printing plate, an inking mechanism for inking the printing plate, an oscillatable scraping blade having an edge for engaging the printing plate for removing 25 the surplus ink from the printing plate, a receptacle for the surplus ink, and means for constantly removing the surplus ink from the scraper and conveying the same into the receptacle in all positions of the 30 scraper.

3. In a mechanism for printing from intaglio printing plates, the combination of an 35 impression member, a printing member for carrying the printing plate, an inking mechanism for the printing plate, a scraper having a sharp edge for removing the surplus ink from the printing plate, a receptacle for the surplus ink, and a carrying surface adapted constantly to remove the surplus 40 ink from the scraper and pass the same directly to the receptacle.

4. In a mechanism for printing from intaglio printing plates, the combination with 45 the bed of an impression member, a printing

member for carrying the printing plate, an inking mechanism for the plate, a scraper for removing the surplus ink from the plate, means for causing the scraper to contact with the printing plate upon alternate movements of the printing member, a receptacle for the surplus ink, and a carrier 50 driven at a faster peripheral speed than the maximum speed of the bed during its printing movement.

5. In a mechanism for printing from intaglio printing plates, the combination of an 55 impression member, a reciprocating printing member for carrying the printing plate, an inking mechanism for the plate, means for removing the surplus ink from the plate, 60 means for causing the removing means to contact with the printing plate upon alternate movements of the latter, a receptacle for the surplus ink, a carrier for removing the surplus ink from the first named 65 means in all positions thereof and passing the same to the receptacle, and means for driving said carrier at a faster peripheral speed than the minimum speed of the printing member during its printing movement. 70

6. In a mechanism for printing from intaglio printing plates, the combination of a 75 scraping blade having a straight edge movable bodily into and out of contact with the plates, a roller constantly in contact with said scraper for receiving ink therefrom in all positions of the scraper, a second scraper having a scraping edge constantly engaging the roller, and a stationary receptacle in position to receive ink from the second scraper. 80

In testimony whereof I have hereunto set my hand, in the presence of two subscribing witnesses.
